REPEATER FUSE SWITCH

Charles Adin Fox, St. Louis, Mo., assignor to
 James R. Kearney Corporation, St. Louis, Mo.,
 a corporation of Missouri

Application October 4, 1940, Serial No. 359,654

4 Claims. (Cl. 200—126)

This invention relates generally to electrical fuse switches of the repeater type and more specifically to a repeater switch of the type disclosed in United States Letters Patent No. 2,209,396, issued on July 30, 1940, the predominant object of the present invention being to provide a repeater switch of the type disclosed in the United States patent identified above, which in addition to being provided with means for slowing the operation of the switch as the effective path of the electrical current is transferred from one set of parts of the switch to another set of parts thereof, includes means for regulating the speed of operation of the switch during the electrical path transfer operation so as to insure such proper speed of operation of the switch that at all voltages properly timed path transfer operations of the switch will be obtained.

The repeater switch disclosed in the United States Letters Patent identified above includes means for slowing the current path transfer operation of the switch whose operation is fixed, regardless of voltage, insofar as the time required for completion of the path transfer operation is concerned. However it is considered advisable under certain circumstances to vary the time required to complete the current path transfer operation of the switch, inasmuch as more time should be provided for completion of such transfer when the switch is associated with lines carrying higher voltages than when the switch is associated with lines carrying lower voltages.

The prime purpose of the present invention, therefore, is to include in the improved switch structure, means adapted on adjustment thereof to accelerate or retard the speed of the current path transfer operation of the switch relative to the basic speed of such operation established by the slowing means. Thus repeater switches of the improved structure may be adjusted before being put in service so that the current path transfer operations of the switches will be accomplished in time periods which will provide for the most efficient operation of the switches at the particular voltages with which they are to be employed.

Fig. 1 is a side elevation of the improved repeater switch disclosed herein.

Fig. 2 is a plan view, on a reduced scale, of the switch illustrated in Fig. 1, a portion of the switch being broken away.

Fig. 3 is an enlarged fragmentary sectional elevation of the slowing means of the switch showing the speed regulating means associated therewith.

Fig. 4 is a front elevation of the structure illustrated in Fig. 3.

Fig. 5 is a fragmentary sectional plan view taken on line 5—5 of Fig. 3.

Fig. 6 is a longitudinal section taken on line 6—6 of Fig. 3.

In the drawings, wherein is shown for the purpose of illustration, merely, one embodiment of the invention, A designates the improved switch generally. The improved switch includes a suitable insulator B to which is attached a bracket C that serves as a means for securing the switch A to a cross arm or other support.

Secured to the insulator B at the upper end thereof is the upper terminal 1 of the switch, said upper terminal including a sectional cap portion 1a which embraces and engages the top portion of the insulator B, and a rigid arm 1b that extends upwardly from said sectional cap portion 1a. The arm 1b of the upper terminal has associated therewith a suitable connector 2 for electrically connecting an electrical conductor Wa to the upper terminal which is a part of the circuit with which the switch A is associated for use. The sectional cap is provided with opposed ears 3 which are provided with apertures through which the end portions of an arcuate rod 4 extend, said rod being arranged in embracing relation with respect to the upper portion of the insulator B and having nuts 4' mounted on its screwthreaded outer ends which serve to draw the arcuate rod and the sectional cap portion 1a of the upper terminal into rigid clamping relation with respect to the insulator.

Associated with the upper terminal 1 is a pair of upper contacts 5 and 6 which preferably, though not necessarily, are formed of heavy wire, each of said upper contacts including an upwardly extended loop portion 7 at its inner end which contacts with a face of the upper terminal, and bolts 8, the shanks of which extend through the loops of said upper contacts, being employed to secure said upper contacts to said upper terminal. Each of the upper contacts 5 and 6 includes a pair of slightly convergent portions which extend forwardly from the loop portion 7 thereof, and at the outer ends of said convergent portions each upper contact is embraced by a sleeve 9 which serves to prevent undue spreading of said convergent portions. Also at the extreme outer end of each of the upper contacts 5 and 6 the forwardly extended, substantially parallel portions of the contact which are continuations of the convergent portions are bent rearwardly upon themselves, as indicated at 10, and the

rearward portions of said rearwardly bent portions are flared outwardly. As will be presently made plain herein the rearwardly bent forward portions 10 of the upper contacts provide gripping portions which receive portions of the fuse links associated with the switch, and the outwardly flared portions serve to guide said portions of the fuse link into said gripping portions. In order to prevent the rearwardly bent portions 10 of the upper contacts from moving outwardly to an unnecessary degree and thereby destroying the gripping action of the fuse link gripping portions of said upper contacts, caps 10' are frictionally applied to the extreme outer end portions of said upper contacts in embracing relation with respect to the outer end portions of said rearwardly bent portions.

The improved switch A includes a pair of lower contacts, one thereof, which is designated by the reference character 11, being attached to the insulator B at a point adjacent to the lower end thereof, and the other lower contact, which is designated by the reference character 12, being attached to the insulator at a point a slight distance above the point of attachment of said lower contact 11. The means for attaching the lower contact 12 to the insulator B includes a member 13 having a portion provided with an arcuate face which is arranged in contact with the curved face of the insulator. The member 13 is secured to the insulator by a curved rod 14 which embraces the insulator in one of the annular depressions thereof, the opposite end portions of said curved rod being extended through openings formed through portions of the member 13 and said opposite end portions of said rod being screwthreaded adjacent to their ends to receive nuts 15 which may be drawn up to cause the curved rod and the member 13 to tightly engage the insulator. The member 13 constitutes the lower terminal of the switch, being provided with an outwardly projected extension 16 which has associated therewith a suitable connector 17 through the instrumentality of which an electrical conductor Wb may be electrically connected to said extension.

The contact 12 preferably is formed from a single length of heavy wire and it includes a horizontal loop 18 at its inner end, said contact 12 being secured to the member 13 by a bolt 19 whose shank extends through the loop 18 of the contact and into an opening formed in said member 13. From the loop 18 portions of the contact 12 extend forwardly and continuations of these portions are bent helically to provide the contact with opposed spring portions 20 which give to the contact the required resiliency.

Leading from the helical spring portions of the lower contact 12 is a pair of parallel contact portions 21 which terminate in convergent portions 22. From the forward ends of the convergent portions 22 parallel and relatively closely positioned contact portions 23 are extended forwardly and at the forward end of the contact these portions 23 are bent rearwardly upon themselves as indicated at 24 to provide gripping portions, similar to the gripping portions of the upper contacts, which are adapted to engage portions of fuse links as will presently appear herein. Extended from the rearwardly bent portions 24 are outwardly flared portions 25 which serve to guide fuse links into the gripping portions. In order to prevent undue spreading of the contact portions 23 sleeves 26 are provided which embrace said portions, and in like manner to pre-

vent excessive outward movement of the rearwardly bent portions 24 a cap 27 is applied to the outer end portion of the contact 12 in embracing relation with respect thereto.

The means for attaching the lower contact 11 to the insulator B comprises a member 28 which is provided with a face that contacts with the outer face of the lower portion of the insulator B (Fig. 4), said member being secured to the insulator by a bolt 29 the shank of which extends through an opening formed through said member and through an aperture formed through the wall of the hollow insulator B.

The lower contact 11 is constructed and arranged just as is the lower contact 12 which has already been described in detail herein; that is to say said lower contact 11 includes a loop 30 at its inner end, opposed helically wound spring portions 31, spaced apart portions 32 which extend forwardly from the lower portions of the spring portions, convergent portions 33, adjacently positioned, forwardly extended portions 34, and rearwardly bent portions 35 at the outer end of the contact which provide gripping portions having flared guides 36 associated therewith. Likewise the contact 11 has a sleeve 37 associated with the portions 34 thereof and a cap 38 applied to the outer end of the contact, the sleeve and cap being intended to prevent undue spreading of parts of the contact. The contact 11 is secured to the insulator by the bolt 29 heretofore referred to, the shank of said bolt passing through the upstanding loop 30 of the contact.

The member 28 that supports the lower contact 11 includes an extension which supports a transfer contact 39. This transfer contact is made preferably from a single length of heavy wire possessed of resiliency and it includes an upstanding loop 39' from the lower end of which forwardly extended portions 40 are projected. At the forward ends of the portions 40 of the transfer contact 39 the length of wire from which the transfer contact is formed is bent upwardly as shown at 41 in Fig. 4. The length of wire is then bent downwardly in parallelism with the portions 41 as shown at 42, and the remaining portions of the length of wire are bent upwardly in spaced relation with respect to the portions 42 as indicated at 43, the upper end portions of said portions 43 being flared outwardly to provide inclined guides 44. The transfer contact is provided with a sleeve 45 which prevents undue spreading of the portions 40 thereof, and said transfer contact is secured to the member 28 by a bolt 46 in the same general manner that the lower contacts 11 and 12 are secured to the members 28 and 13.

In its fully fused condition the improved switch includes a pair of fuse links 47 and 48 of like construction and arrangement. Each of these fuse links comprises a pair of flexible cables 49 which are spaced apart at their inner ends to provide a gap, and a fusible element (not shown) which is electrically connected to the inner end portions of said cables is disposed in said gap. The fusible element and the adjacent inner portions of the flexible cables 49 of each fuse link are enclosed within a tube 50 which preferably is formed of horn fiber or other material that is characterized by the ability to give off a gas in the presence of the heat of an electric arc which tends to extinguish said electric arc. The tube 50 of each fuse link is interposed between and is supported by a collar 51 and a coil spring 52 that are supported by the cables 49. At the outer ends

of the cables 48 of each fuse link loops 53 are formed and fixed to the flexible conductors in close proximity to the loops are stop buttons 54.

When the improved switch is fully fused the lower flexible cable of the fuse link 48 is drawn into one of the gripping portions at the outer end portion of the lower contact 11, while the lower flexible cable of the fuse link 47 is drawn into one of the gripping portions at the outer end portion of the lower contact 12. Also during the fully fused position of the improved switch the upper flexible cables of the fuse links 47 and 48 are drawn into gripping portions of the upper contacts 5 and 6, the upper flexible conductor of the fuse link 47 being drawn into a gripping portion of the upper contact 5, while the upper flexible cable of the fuse link 48 is drawn into a gripping portion of the upper contact 6.

In assembling the fuse links 47 and 48 in place with the switch said fuse links are applied to the switch one at a time. Ordinarily the switch is located in an elevated position and when this is so the operator passes the transverse finger of a fuse stick through the loop at the upper end of the fuse link so that the link is suspended from said finger. He then raises the suspended fuse link and pulls it outwardly so as to draw the portion of the lower flexible cable immediately above the button 54 deep into the gripping portion of the lower contact with which the fuse link is being assembled. The operator then raises the fuse link to the proper elevation and then pulls the upper portion of said fuse link outwardly so as to draw a portion of the upper flexible cable deep in one of the gripping portions of the appropriate upper contact. When the operator raises the fuse link with its lower end attached to a lower contact he winds the helical spring portions of the lower contact with the result that said lower contact is placed under considerable tension which tends to draw the outer end of the lower contact downwardly. When the first fuse link has been applied to the switch as described the second fuse link is assembled with the switch in like manner whereupon the switch is ready for use.

When the improved switch is fully fused and in use electrical energy passes from the terminal 1, through the upper contact 5 to and through the fuse link 47 to the lower contact 12, and from said lower contact through the lower terminal 13 to the conductor connected thereto. It is to be noted that when the switch is fully fused no current passes through the fuse link 48 due to the fact that the lower contact 11 is out of electrical connection with respect to the lower terminal 13. Now, if with the switch fully fused a fault occurs in the circuit, the fusible element of the fuse link 47 will part and thereby release the tensioned lower contact 12 which will move downwardly in response to action of the helical spring portions 28. This will quickly separate the severed ends of the ruptured fusible element so as to quickly extinguish the electric arc produced by severance of the fusible element, such extinguishment of the electric arc being aided by the gas produced within the tube 59 when the horn fiber thereof is subjected to the heat of the electric arc.

When the outer portion of the lower contact 12 is moved downwardly as described the forwardly extended portions 23 of said lower contact 12 move into the spaces between the upright portions 42 and 43 of the transfer contact 39. The course of the current then is from the upper terminal through the upper contact 5, to and 75

through the fuse link 48 to the lower contact 11. From the lower contact the current passes through member 28 with which the lower contact 11 is associated to the transfer contact 39 and from said transfer contact to and through the lower contact 12, which at this time contacts with the transfer contact 39, to the lower terminal 13 and the conductor connected thereto.

The member 13 which serves as the lower terminal of the switch includes an outwardly and upwardly inclined housing portion 55 which preferably though not necessarily, is of the shape illustrated to the best advantage in Fig. 3. The housing portion 55 is open at its opposite sides 56 which is closed at one of its sides by a fixed wall 56a and at its opposite side by a removable wall 56b which is secured in place by means of suitable fastening devices. Supported for rotation by the opposed side walls of the casing 55 is a shaft 57 on which is fixedly mounted a gear wheel 58 of relatively large diameter. The gear wheel 58 meshes with a pinion 59 (Fig. 6) which is mounted for rotation on a shaft 60 that is non-rotatably supported by the side walls of the casing 55, and said pinion is provided with a hub or sleeve portion 61 on which a gear wheel 62 is fixedly mounted. The gear wheel 62 in turn meshes with a pinion 63 which is loosely mounted on the shaft 57 for rotary movement with respect thereto, and this pinion is provided with a hub or sleeve portion 64 on which a gear wheel 65 is fixedly mounted. The gear wheel 65 meshes with a pinion 66 which is supported by the fixed shaft for rotation with respect thereto, and said pinion 66, which is of elongated shape, has splined, or otherwise secured thereto, a fly wheel 68.

From the foregoing arrangement it is obvious that when the shaft 57 is rotated rotary motion will be imparted by the gear wheel 58 fixed to said shaft 57 to the pinion 59 and because of the relative sizes of the gear wheel 58 and the pinion 59 the speed of rotation of the pinion will be much greater than the speed of rotation of the gear wheel. Also rotation of the pinion 59 will be transmitted by the gear wheel 62 fixed to said pinion, to the pinion 63 mounted for rotation relative to the shaft 57 and here also the speed of rotation of the pinion 63 will be greatly increased because of the relative sizes of the gear wheel 62 and the pinion 63. Additionally, rotation of the pinion 63 will be transferred by the gear wheel 65 fixed to said pinion to the pinion 66 with a consequent increase in speed of rotation of the pinion 66 due to the relative sizes of said gear wheel and pinion, and because the fly wheel 68 is fixed to the pinion 66 it will rotate therewith at a rate of speed greatly in excess of the speed of rotation of the shaft 57.

Fixed to the shaft 57 adjacent to the opposite ends thereof are the spaced portions 70a of a bifurcated arm 70, said spaced portions 70a of said arm being arranged to straddle the housing 55 as shown in Fig. 6 and the outer end portion 70b of said arm being extended outwardly beyond said housing as shown in Fig. 3. The outer portion 70b of the bifurcated arm 70 has formed therethrough a row of apertures 71 as is shown to the best advantage in Figs. 1 and 3. Fixed to the portions 21 of the lower contact 12 is a member 72 which comprises a lower flat sheet 73 of material which at its opposite side edges is provided with upwardly curved portions 74 that partially embrace the opposed portions 21 of the lower

contact 12, said opposed, curved portions having extended upwardly therefrom flanges 75 through each of which a row of apertures 76 is formed. At the forward and rear edges of the flat sheet of material 73 extensions 77 are formed which, before the member 72 is applied to the portions 21 of the lower contact 12, are alined with the flat sheet of material 73, these extensions when the member 72 is being applied to said portions 21 of the lower contact 12 being bent upwardly so that the curved edges at the opposite ends of the extensions frictionally engage the inner portions of the faces of said portions 21 of the lower contact 12, as shown in Fig. 5. Thus, because the opposed curved portions of the member 72 frictionally engage the outer portions of the faces of the portions 21 of the lower contact 12, and the curved edges of the extensions 77 of said member 72 frictionally engage the inner portions of said portions 21 of said lower contact 12, the member 72 is securely clamped in a fixed position to said portions 21 of said lower contact 12.

Associated with the bifurcated arm 10 and the member 72 is a connecting link 78 which is substantially of inverted U-shaped formation, said connecting link including a bridge portion 78a which is extended through one of the apertures 71 formed through the portion 10b of the bifurcated arm 10, and spaced, side portions 78b which extend downwardly from said bridge portion and are provided with inwardly projected portions 78c at their lower ends which are extended through apertures 76 formed in the flanges 75 of the member 72. The spaced, side portions of the connecting link 78 have mounted thereon an elongated plate 79 which at one of its ends is provided with an enclosed aperture 80 formed therethrough through which one of the side portions 78b of the connecting link extends. Adjacent to its opposite end the elongated plate 79 has formed therein an elongated aperture 81 into which a slot 82 leads which is open at an edge of the elongated plate 79, the opposite side portion of the connecting link 78 being extended through said elongated aperture 81 as shown in Fig. 5. The elongated plate 79 serves, when in its effective position relative to the connecting link 78, to prevent the side portions 78b of said connecting link from moving outwardly and thus permitting the inwardly projected portions 78c to become disengaged from the apertures 76 of the flanges 75 of the member 72. However when it is desired to detach the connecting link from the member 72 the side portion 78b of the connecting link which passes through the elongated opening 81 may be moved inwardly slightly until said portion is alined with the narrower slot 82, whereupon the elongated plate may be swung about the opposite side portion 78b of the connecting link to disengage the end of the elongated plate in which the elongated opening 81 is formed from the corresponding side portion of the connecting link and permit detachment of the connecting link from the flanges 75 of the member 72.

When in the operation of the improved switch disclosed herein the fuse link 47 is ruptured, the outwardly extended portion of the lower contact 12 is freed from restraint and as a result of the tension stored up in the spiral spring portions 20 said extended portion of said contact immediately starts to move downwardly toward the transfer contact 39. However, because the additional burden of rotating the fly wheel 68 and the speed reducing gearing associated therewith is applied to the downwardly moving contact 12 its speed of

movement is reduced to a substantial degree with the result that sufficient time is available under any and all conditions to interrupt the passage of current through the path of which the ruptured fuse link forms a part before the new path of current is established. Also because energy is stored up in the rapidly rotating fly wheel as the contact 12 moves toward the transfer contact 39 this energy, which is in the form of centrifugal force, drives the contact portions 23 of the contact 12 deep into tight contact with portions of the transfer contact to make good electrical contact between these parts.

The important feature of this invention is that, because of the plurality of apertures 71 formed in the bifurcated arm 10 and the plurality of apertures 76 formed in the flanges 75 of the member 72, the speed of movement of the lower contact 12 may be accelerated or retarded to provide for the proper timing of the current path transfer operation of the switch when the switch is employed with lines carrying current. This is accomplished by merely shifting the connecting link longitudinally of the portion 10b of the bifurcated arm 10 and of the member 72 to apertures thereof which will provide the leverage to give the desired speed of movement of the lower contact 12 as it moves downwardly toward the transfer contact 39.

I claim:

1. A repeater fuse switch comprising a support, a terminal supported by said support, contact means supported by said support in electrical contact with said terminal, a pair of contacts supported by said support in spaced relation with respect to said contact means and having portions which tend to move in a direction away from said contact means, a second terminal supported by said support in electrical contact with one of said pair of contacts, a pair of fuse links electrically connected to said pair of contacts and to said contact means and held under tension by the tendency of the movable portions of said pair of contacts to move in a direction away from said contact means, a transfer contact into electrical contact with which one of said pair of contacts moves when the fuse link of said one of said contacts is ruptured, means for retarding the speed of movement of said one of said pair of contacts as it moves toward said transfer contact, said speed retarding means including an arm arranged for arcuate movement and having a plurality of apertures formed therein, a member fixed to said one of said pair of contacts and having spaced portions having each a plurality of apertures formed therein, and an element of inverted U-shaped formation connected to said arm of said speed retarding means and to said member of said one of said pair of contacts, portions of said element being disposed in apertures of said arm and of said spaced portions of said member and said portions of said element being adjustable to different apertures of said arm and said spaced portions of said member to vary the speed of movement of said one of said contacts from the speed of movement thereof established by said speed retarding means.

2. A repeater fuse switch comprising a support, a terminal supported by said support, contact means supported by said support in electrical contact with said terminal, a pair of contacts supported by said support in spaced relation with respect to said contact means and having portions which tend to move in a direction away from said contact means, a second terminal supported by

said support in electrical contact with one of said pair of contacts, a pair of fuse links electrically connected to said pair of contacts and to said contact means and held under tension by the tendency of the movable portions of said pair of contacts to move in a direction away from said contact means, a transfer contact into electrical contact with which one of said pair of contacts moves when the fuse link of said one of said contacts is ruptured, means for retarding the speed of movement of said one of said pair of contacts as it moves toward said transfer contact, said speed retarding means including an arm arranged for arcuate movement and having a plurality of apertures formed therein, a member fixed to said one of said pair of contacts and having spaced portions having each a plurality of apertures formed therein, an element of inverted U-shaped formation connected to said arm of said speed retarding means and to said member of said one of said pair of contacts, portions of said element being disposed in apertures of said arm and of said spaced portions of said member and said portions of said element being adjustable to different apertures of said arm and said spaced portions of said member to vary the speed of movement of said one of said contacts from the speed of movement thereof established by said speed retarding means, and means for preventing the portions of said element which are disposed in apertures of said spaced portions of said member of said one of said pair of contacts from being unintentionally displaced from said apertures.

3. A repeater fuse switch comprising a support, a terminal supported by said support, contact means supported by said support in electrical contact with said terminal, a pair of contacts supported by said support in spaced relation with respect to said contact means and having portions which tend to move in a direction away from said contact means, a second terminal supported by said support in electrical contact with one of said pair of contacts, a pair of fuse links electrically connected to said pair of contacts and to said contact means and held under tension by the tendency of the movable portions of said pair of contacts to move in a direction away from said contact means, a transfer contact into electrical contact with which one of said pair of contacts moves when the fuse link of said one of said contacts is ruptured, means for retarding the speed of movement of said one of said pair of contacts as it moves toward said transfer contact, said speed retarding means including an arm arranged for arcuate movement and having a plurality of apertures formed therein, a member fixed to said one of said pair of contacts and having spaced portions having each a plurality of apertures formed therein, an element of inverted U-shaped formation connected to said arm of said speed retarding means and to said member of said one of said pair of contacts, portions of said element being disposed in apertures of said arm and of said spaced portions of said member and said portions of said element being adjustable to different apertures of said arm and said spaced portions of said member to vary the speed of movement of said one of said contacts from the speed of movement thereof established by said speed retarding means, and means for preventing the portions of said element which are disposed in apertures of said spaced portions of said member of said one of said pair of contacts from being unintentionally displaced from said apertures, said means comprising an elongated part which engages opposed leg portions of said element.

5 of said pair of contacts, portions of said element being disposed in apertures of said arm and of said spaced portions of said member and said portions of said element being adjustable to different apertures of said arm and said spaced portions of said member to vary the speed of movement of said one of said contacts from the speed of movement thereof established by said speed retarding means, and means for preventing the portions of said element which are disposed in apertures of said spaced portions of said member of said one of said pair of contacts from being unintentionally displaced from said apertures, said means comprising an elongated part which engages opposed leg portions of said element.

4. A repeater fuse switch comprising a support, a terminal supported by said support, contact means supported by said support in electrical contact with said terminal, a pair of contacts supported by said support in spaced relation with respect to said contact means and having portions which tend to move in a direction away from said contact means, a second terminal supported by said support in electrical contact with one of said pair of contacts, a pair of fuse links electrically connected to said pair of contacts and to said contact means and held under tension by the tendency of the movable portions of said pair of contacts to move in a direction away from said contact means, a transfer contact into electrical contact with which one of said pair of contacts moves when the fuse link of said one of said contacts is ruptured, means for retarding the speed of movement of said one of said pair of contacts as it moves toward said transfer contact, said speed retarding means including an arm arranged for arcuate movement and having a plurality of apertures formed therein, a member fixed to said one of said pair of contacts and having spaced portions having each a plurality of apertures formed therein, an element of inverted U-shaped formation connected to said arm of said speed retarding means and to said member of said one of said pair of contacts, portions of said element being disposed in apertures of said arm and of said spaced portions of said member and said portions of said element being adjustable to different apertures of said arm and said spaced portions of said member to vary the speed of movement of said one of said contacts from the speed of movement thereof established by said speed retarding means, and means for preventing the portions of said element which are disposed in apertures of said spaced portions of said member of said one of said pair of contacts from being unintentionally displaced from said apertures, said means comprising an elongated part which engages opposed leg portions of said element, in such manner that it may be designedly detached from one of said leg portions of said element.

CHARLES ADIN FOX.
